(57) **CLAIM**

The ornamental design for a telescoping monitor mount, substantially as shown and described.

DESCRIPTION

FIG. 1 is a rear isometric view of a telescoping monitor mount, showing our new design in a first state;

FIG. 2 is a rear isometric view thereof in a second state;

FIG. 3 is a rear view thereof in the first state;

FIG. 4 is a rear view thereof in the second state;

FIG. 5 is a front view thereof in the first state;

FIG. 6 is a front view thereof in the second state;

FIG. 7 is a first side view thereof;

FIG. 8 is a second side view thereof;

FIG. 9 is a bottom plan view thereof in the first state; and,

FIG. 10 is a top plan view thereof in the first state.

Any features shown in broken lines form no part of the claimed design.

1 Claim, 10 Drawing Sheets
